TOY TRAIN AQUARIUM CAR

Gerald Matyas, Wharton, N.J., assignor to The Lionel Corporation, New York, N.Y., a corporation of New York

Filed Feb. 17, 1960, Ser. No. 59,432

Term of patent 14 years

(Cl. D34—15)

Fig. 1 is a side elevational view of a toy train aquarium car from either side.

Fig. 2 is an end elevational view of either end of Fig. 1 in accordance with my design; and

Fig. 3 is a top plan view of the toy train aquarium car. The dominant features of my design reside in the portions shown in full lines.

This application is a continuation-in-part of applicant's prior co-pending application Serial No. D.56,516, filed June 24, 1959, now abandoned.

I claim:

The ornamental design for a toy train aquarium car, as shown and described.
